UNITED STATES PATENT OFFICE

JOHN E. JOHNSON, OF AURORA, ILLINOIS

DIE-SINKING AND ENGRAVING MACHINE

Application filed September 23, 1929. Serial No. 394,610.

This invention relates to that class of die-sinking and engraving machines having an upwardly and downwardly movable tool-supporting member mounted upon and movable with and with respect to a tool-supporting carriage, which is capable of universal movement in any and all directions in a horizontal plane and having means for controlling the movement of the tool and carriage, and means for driving the tool.

The principal object of the invention is to provide a simple, economical and efficient die-sinking and engraving or cutting machine; and more particularly to provide an improved die-sinking and engraving machine having a tool holding member and guiding member or stylus mounted upon and movable upwardly and downwardly with respect to a supporting carriage which is adapted to be moved universally in any and all directions in a horizontal plane concurrently with the operation of the tool and tool guiding means or stylus, and provided with means for driving the tool and operating the carriage.

Other and further objects of the invention will appear from the following description and claims, and from an inspection of the accompanying drawings which are made a part hereof.

The invention consists of the features, combinations, details of construction and arrangement, and mode of operation of parts as herein described and claimed.

In the accompanying drawings,

Figure 1 is a plan view of an improved die-sinking and engraving machine constructed in accordance with my invention;

Fig. 2 is a view in side elevation of the machine shown in Fig. 1, with part of the tool-supporting mechanism and work supporting means shown in section;

Fig. 3 is a front view in elevation of the upper part of the machine shown in Figs. 1 and 2; and

Fig. 4 is an enlarged detail view of the feed screw mechanism for operating the carriage or tool-supporting means in a horizontal plane.

In constructing an improved die-sinking

and engraving machine in accordance with my invention, I provide a stationary bed or frame 1, which is, by preference, provided with an adjustable work-supporting bed 2 mounted thereon.

The work-supporting bed 2 is supported upon and in upwardly and downwardly adjustable relation to the stationary bed or frame 1, by means of a forwardly projecting frame or bracket 3, having a vertical depending frame arm 4 which is adapted to slidably engage the vertical face of an upright guiding frame portion 5 on the stationary frame 1, said upright guiding members 4 and 5 having tongued and grooved connection with each other.

In the device shown in the drawings, the upright depending frame arm 4 is provided with a vertically elongated guiding groove 6 which is adapted to admit and slidably engage a corresponding vertical guiding tongue on the adjacent guiding frame member 5; and an upright bed-supporting feed-screw 7 is mounted in screw-threaded engagement with a rigid supporting socket 8 fixed to the bottom portion of the stationary frame 1, the upper end of said screw being seated in a socket or bearing 9 on the work supporting bed 2, and provided with a hand wheel 10 for operating said screw to raise and lower the work supporting bed 2 with the work 11 and pattern 12 thereon to any desired position relatively to the stationary bed or frame 1 and the mechanism supported thereon.

The work 11 or material to be operated upon, and the pattern 12, are both mounted upon and firmly secured in rigid relation to each other upon the adjustable work supporting bed 2. The usual headed securing bolts 13 are mounted with the bolt heads in horizontal elongated bayonet slots 14 in the flat top surface of said bed 2, the upper ends of said bolts being adapted to extend through suitable openings in the flanged clamping blocks 15 which are secured by said bolts and nuts 16 thereon in rigid clamping engagement with the bottom flange portions 17, or other suitably formed

parts of the work 11 and patterns 12 respectively. (See Figs. 2 and 3).

Mounted upon and movable in a horizontal plane relatively to the stationary base 5 or frame 1 is a tool-supporting carriage or frame 18 which is adapted to be moved backward and forward upon parallel grooved supporting tracks 19 on the stationary bed 1; and ball bearings 20 are interposed between the carriage and said supporting track, and adapted to travel in elongated horizontal grooves in the tracks and parallel horizontal elongated grooves 22 in said tool-supporting frame or carriage 18.

15 (See Fig. 3.)

A tiltable or rocking tool-supporting frame 23 is tiltably supported upon and movable in a horizontal plane with and with respect to the carriage 18 and adapted 20 to support in operative position and in upwardly and downwardly movable relation to the carriage 18 and the work 11 and pattern 12, a tool 24, which is rotatively supported in suitable bearings in a tool-holder 25 fixed to a tiltable frame arm 26 which is on and forms a part of the tiltable frame 23. A guiding stylus 27 is mounted upon a similar upwardly and downwardly movable stylus supporting frame arm 28 and supported in fixed parallel relation to and movable with the tool.

The tiltable tool-supporting frame arm 26 and stylus supporting frame arm 28 are fixed to a horizontal rock shaft 29 which 35 forms a part of said tiltable frame 23.

A rigid tiltable tool-supporting and stylus-supporting frame 23 is thus provided which comprises a rigidly connected tool-supporting arm 26, stylus-supporting arm 28 and 40 rock shaft or track-rod 29, all of which are tiltably supported upon and movable in a horizontal plane relatively to the carriage 18, by preference, as follows:

Rotatively supported upon and carried by 45 the carriage 18 is a pair of circumferentially grooved track-supporting and guiding wheels 30 each of which is, by preference, fixed to a horizontal axle 31, the opposite ends of each of said axles being journaled in bearings 32 on the carriage.

Each of the bearings 32 comprises, by preference, a pair of upright flanged bearing members 35 and 36, which are rigidly secured to transversely projecting carriage 55 frame members 33 and 34 respectively, by means of bolts 37 which extend through suitable openings in said bearing members and the frame members located therebetween, or other suitable securing means.

60 Each of the inner bearing members 35 is provided with a central opening through which the axle 31 of the adjacent grooved wheel 30 extends. Each of the outer bearing members 36 is provided with an adjustable screw-threaded end-thrust bearing

pin 38 which extends through the central opening in such bearing member 36 and in abutting engagement with the end of the adjacent axle 31. The inner ends of the end-thrust bearing pins 38 are, by preference, conical and adapted to extend into similarly tapered conical end openings in said axle. The bearings 32 with the adjustable end-thrust bearing pins 38 are thus adapted to hold the axles 31 in parallel relation to each other and to hold the corresponding grooved wheels 30 in proper alignment and in position to support and guide the horizontal rocking track-rod 29 and tiltable supporting frame 23 in accurately adjusted and aligned operative position upon the carriage.

The tool-holder or chuck 25 in which the cutting tool or drill 24 is operatively supported upon the arm 26 of the tool-supporting frame 23 may be of any ordinary, well known or suitable form adapted to rotatively support the cutting tool or drill in operative position during the operation of the machine: For example, an outer split-sleeve or head 40 is rigidly mounted upon and may be formed integrally with the arm 26 on the tiltable tool-supporting frame 23, and is provided with side flanges 41 and 42 having suitable openings into which a

clamping bolt 43 is inserted in screw-threaded engagement with one of said flanges, for clamping the flanged margins of the split-sleeve or head 40 together, and for releasing the same. An inner cylindrical sleeve or bushing 42' is mounted in and adapted to be securely clamped and held in operative position by the clamping-sleeve or head 40 and is provided with a vertical axial opening 43' forming a journal bearing in which is rotatively mounted a rotative vertical inner chuck member or spindle 44, the lower end of which is provided with suitable clamping jaws 45 adapted to releasably engage and hold in rigidly clamped operative position the cutting tool or drill 24, which may be of any well known or suitable form for cutting the material to be operated upon.

Suitable driving means is provided and mounted upon the tiltable tool-supporting frame, for operating the cutting tool, and comprises, by preference, a belt pulley 45' fixed to the upper projecting end of the rotative tool-supporting spindle 44, and operatively connected with an electric motor

46 which is mounted upon the tiltable frame 23 and provided with electric wires 47 connected with the opposite poles of the motor and adapted to connect with a suitable source of power. The motor is connected with the tool-supporting spindle 44 by means of a belt pulley 48 fixed to the motor shaft 49; and a belt 50 is mounted upon and adapted to operatively connect said belt pulleys 45' and 48 on the tool-supporting spin-

dle and motor shaft respectively. By thus providing driving means which is mounted upon the same tiltable and horizontally movable frame with the cutting tool and guiding stylus, the operator is enabled to raise and lower and move the cutting tool and stylus in any and all directions as required during the operation of the machine without affecting or interfering with the operation of the driving mechanism or the means for connecting the cutting tool with the driving mechanism and source of power.

The stylus 27, above mentioned, is in the form of an upright spindle, having a screw-threaded main body portion 51 which is mounted in a cylindrical sleeve or bushing 52 having a vertical screw-threaded axial opening adapted to engage and permit the adjustment of the stylus upwardly and downwardly in the bushing, by rotating the stylus in one direction for raising, and in the opposite direction for lowering the same. The stylus-supporting sleeve or bushing 52 is rigidly secured in operative position in an upright split clamping sleeve or head 53, which is fixed to the outer projecting end of the tiltable frame arm 28. Said split-sleeve has perforated side flanges 54 which are drawn together by a horizontal clamping screw 55, which is mounted in the perforations in said flanges, the threaded end of the screw being in screw-threaded engagement with one of the flanges and the head in engagement with the other. (See Fig. 1.)

A head 56 on the upper projecting end of the stylus serves as a convenient means for enabling the operator to turn the stylus to adjust it upward and downward in its support; and a set screw 57 seated in a suitable screw-threaded opening in the stylus-supporting sleeve or bushing 52 and in engagement with the stylus serves to firmly secure the latter in any desired adjusted position.

The axes of the normally upright guiding stylus 27 and of the normally upright cutting tool 24 and its supporting spindle are parallel; and the stylus and tool thus supported on the same tiltable frame 23, are movable concurrently in constant parallel relation to each other in any desired direction in a horizontal plane to any desired position while the point of the stylus is in engagement with a pattern and the point of the cutting tool is simultaneously in engagement with and adapted to operate upon a corresponding part of the die or object to be cut according to such pattern. The guiding stylus and tool are also adapted to be moved in parallel constant uniform relation to each other upward and downward with the forwardly projecting arms of the tiltable horizontally movable tool-supporting frame 23, and simultaneously in any desired direction in a horizontal

plane. The guiding stylus and cutting tool are, by preference, located at equal distances from the horizontal axis of the tiltable frame 23 and guiding track rod 29 on which they are mounted; and the pattern and work are supported in fixed position relatively to each other and at equal distances from the horizontal axis of the tiltable tool-supporting frame 23 and said guiding track rod. The guiding stylus and tool are so supported upon the tiltable frame that their bottom ends are always in the same horizontal plane relatively to each other and in substantially the same horizontal plane with the axis of the tiltable frame and guiding track or rod 29 when the cutting tool is in cutting engagement with the work. The bottom ends of the stylus and cutting tool are, by preference, of substantially the same size and contour, and the point of the stylus is thus adapted to be moved into and out of contact with the pattern, drawing or design at any desired point, or to be moved into contact with the surface of a pattern to be copied or duplicated whether the surface is uniform or irregular and varied in contour. And the cutting tool is adapted to be guided and caused to move in engagement with the work concurrently with and in exact conformity with the movements of the point of the stylus in contact with the pattern and in any and all directions as required.

Manually operative feeding mechanism is provided for enabling the carriage and tiltable tool-supporting frame 23 and the guiding stylus and cutting tool supported thereon, to be moved in any and all directions in a horizontal plane to any desired operative position relatively to the pattern and work and adapted to enable said tiltable frame to be tilted and the cutting tool and stylus to be raised and lowered as required with facility and without interfering with the operation of said manually operable means, as follows:

A horizontal feed screw 58 is rotatably supported at one end in a bearing 59 on an upwardly projecting frame arm 60 on the carriage 18.

Mounted adjacent to and in position to be moved into and out of screw-threaded engagement with the feed screw 58 is a stationary screw-threaded member 61 which is, by preference, in the form of a lever pivotally mounted upon a head 62 on the upper end of the stationary bracket arm 63 by means of a hinge pin 64 on said head and extending through a suitable opening in said lever. The lever 61 is provided with a segmental or substantially half-round screw-threaded collar or nut portion 65 which forms a stationary threaded nut and is adapted to be moved into and out of screw-threaded engagement with the feed

screw by the movement of the lever upon its axis. The head 62 has a half-round opening 66 opposite the nut 65 through which the feed screw extends. The swinging end of the screw-threaded lever 61 is operatively connected with the pedal 67 for operating said screw-threaded lever 61 to move it into and out of engagement with the feed screw 58 for moving the carriage 18 lengthwise of the tracks 19.

In the device shown in the accompanying drawings, the pedal 67 is on one of the arms of an oscillating bell-crank lever 68 on the machine frame. An intermediate bell-crank 69 is pivotally supported on the frame 1 by means of a horizontal pivot pin 70. An upright lever arm 71 on the bell-crank 69 is connected with the upright arm 68 of the pedal lever by means of a connecting rod 72; and a horizontal lever arm 73 on the bell-crank 69 is connected with the stationary threaded feed screw engaging lever 61 by means of an upright connecting rod 74, the upper end of which is provided with forked arms having a connecting pin 75 seated therein and extending through a suitable opening in the end of said lever. (See Figs. 1, 2, 3 and 4.)

A rotative handle 76 fixed to a stub-shaft 80 journaled in a supporting bearing 77 in the stylus-supporting head 53, already described, is flexibly connected with the rotative feed screw 58 by means of a connecting rod 78 which forms an extension of said feed screw, one end of said connecting rod being flexibly connected with the adjacent forked front end of the feed screw by a universal joint 79, and the other end of said connecting rod being connected with the rotative handle 76 and stub-shaft 80 which forms an extension of said handle by means of a universal joint 81. The feed screw is thus adapted to be operated by rotating the feed screw handle 76 in one direction to cause the carriage 18 to move forward on the track 19 on the stationary frame 1, and in an opposite direction to cause the carriage to move rearward on said tracks and stationary frame.

In order to provide simple and efficient means for operating this tilting frame in a horizontal plane in opposite directions at right angles to the tracks 19, and at right angles to the direction in which the carriage is adapted to move by the feed screw 58, a toothed rack 82 is flexibly supported at one end upon a projecting frame arm 83 on the carriage 18 and extends through and in slidable engagement with a bearing 80 or socket 84 on the tool-supporting head 40 on the frame arm 26 of the tiltable tool-supporting frame 23. A toothed pinion 85 is fixed to a horizontal rotative stub-shaft 86 which is journaled in a bearing 87 in the split-sleeve or head 40; and a handle 88 is

fixed to said stub-shaft 86 for rotating the same to operate said pinion to cause the pinion 85 and the carriage 18 to move horizontally lengthwise of the stationary rack in either direction at right angles to the direction in which the carriage is adapted to be moved by the feed screw 58, as required. From the foregoing description it will be readily understood that the rotative handle 76 being mounted on and tiltable with the 75 tiltable tool-supporting frame 23 and flexibly connected with the feed screw 58 by means of the connecting rod 78 and universal joints, the operator is enabled to rotate the feed screw by means of said handle 76 while the tiltable frame and said handle are in any desired position, and concurrently with the movement of the tool the stylus in any direction either upward or downward or horizontally when the machine is in operation. The rotative handle 88 with its rack-engaging pinion 85 being mounted upon the same tiltable frame with the feed screw operating handle 76, the operator is thus enabled to operate the handle 76 with one hand to cause the carriage to move in either direction on its supporting tracks 19, and to simultaneously operate the handle 88 with his other hand, to cause the tiltable tool-supporting frame to move in either direction at an angle to the direction of movement of the carriage. It is, therefore, obvious that a machine constructed in accordance with my invention, as above described and shown, and provided with my improved tool-supporting and feeding means, is adapted to enable the operator to cause the cutting tool and stylus or tracer to move concurrently in constant unvarying relation to each other in any and all directions relatively to the stationary work and pattern and with great facility and accuracy.

I claim:

1. In a mechanism of the class described, the combination of a horizontally movable carriage, means for guiding said carriage in a horizontal plane, a horizontal longitudinally movable rocking track rod disposed at right angles to the path of movement of said carriage, a tiltable tool-supporting frame supported on and movable with said rocking track rod and adapted to tilt upon the horizontal axis of said rod, a pair of grooved supporting wheels journaled in suitable bearings on said carriage and in supporting engagement with said rocking track rod, a tool rotatively mounted on said tiltable frame, a guiding stylus supported in fixed relation to said tool for guiding the same, manually operable feeding means operatively connected with said carriage and said tiltable tool-supporting frame for moving the same relatively to each other, means for supporting a pattern and material to be operated upon in position to 130

be concurrently engaged by said stylus and tool respectively, and driving means on and movable with said carriage and operatively connected with said tool for rotating the same.

same.

2. In a mechanism of the class described, the combination of a horizontally movable carriage, means for guiding said carriage, a tiltable tool-supporting frame mounted on
10 said carriage and adapted to tilt on a horizontal axis disposed at right angles to the direction of movement of the carriage, a tool rotatively mounted on said tiltable frame, a guiding stylus supported on said
15 tiltable frame in fixed relation to said tool and adapted to be moved concurrently with the tool while the stylus is in contact with a guiding pattern and the cutting tool in contact with material to be operated upon,
20 driving means on and movable with said carriage and connected with said tool for rotating the same, feeding mechanism comprising a feed screw rotatively mounted upon and movable with said carriage, a stationary screw-threaded member in screw-threaded engagement with said screw and adapted to effect the movement of the carriage when the feed screw is rotated, and a
25 handle rotatively supported on said tiltable tool-supporting frame and operatively connected with said feed screw for rotating the same to effect the movement of the carriage.

30

3. In a mechanism of the class described, the combination of a horizontally movable carriage, means for guiding said carriage, a tiltable tool-supporting frame mounted upon said carriage and adapted to tilt upon a horizontal axis disposed at right angles to the direction of movement of the carriage, a tool rotatively mounted on said tiltable frame, a guiding stylus supported on said tiltable frame in fixed relation to said tool and adapted to be moved concurrently with the tool while the stylus is in contact with a guiding pattern and the cutting tool in contact with material to be operated upon, driving means on and movable with said carriage and connected with said tool for rotating the same, feeding mechanism comprising a feed screw rotatively mounted upon and movable with said carriage, a stationary screw-threaded member in screw-threaded engagement with said screw and adapted to effect the movement of the carriage when the feed screw is rotated, and feeding means supported on the carriage and operatively connected with said tiltable tool-supporting frame and adapted to effect the movement of the same in a direction at right angles to the direction of the path of movement of said carriage.

4. In a mechanism of the class described, the combination of a horizontally movable carriage, means for guiding said carriage, a
tiltable tool-supporting frame mounted on

70
75
80
85
90
95
said carriage and adapted to tilt on a horizontal axis disposed at right angles to the direction of movement of the carriage, a tool rotatively mounted on said tilttable frame, a guiding stylus supported on said tilttable frame in fixed relation to said tool and adapted to be moved concurrently with the tool while the stylus is in contact with a guiding pattern and the cutting tool in contact with material to be operated upon, driving means on and movable with said carriage and connected with said tool for rotating the same, feeding mechanism comprising a feed screw rotatively mounted upon and movable with said carriage, a stationary threaded member in toothed engagement with said screw and adapted to effect the movement of the carriage when the feed screw is rotated, a handle rotatively supported on said tilttable tool-supporting frame and operatively connected with said feed screw for rotating the same to effect the movement of the carriage in a horizontal plane, and feeding means supported on the carriage and operatively connected with said tilttable tool-supporting frame and adapted to effect the movement of the same in a direction at right angles to the direction of the path of movement of said carriage.

5. In a mechanism of the class described, the combination of a horizontally movable carriage, means for guiding said carriage, a tiltable tool-supporting frame mounted on said carriage and movable in a horizontal plane at an angle to the direction of the path of movement of said carriage, a tool rotatively mounted on and movable upwardly and downwardly with said tiltable tool-supporting frame, a guiding stylus supported in fixed relation to and movable concurrently with said tool, driving means supported on and movable with said carriage and operatively connected with said tool for rotating the same, feeding mechanism operatively connected with said carriage and adapted to move the same in a horizontal plane, and feeding mechanism supported on said carriage comprising a toothed rack flexibly connected with the carriage and a toothed pinion rotatively supported on the tiltable frame and adapted to engage said rack, for moving the tiltable frame in a direction at right angles to the direction of movement of the carriage. 100 105 110 115 120

6. In a mechanism of the class described, the combination of a horizontally movable carriage, means for guiding said carriage, a tilttable tool-supporting frame mounted on said carriage and adapted to tilt on a horizontal axis disposed at right angles to the direction of movement of the carriage, a tool rotatively mounted on said tilttable frame, a guiding stylus supported on said tilttable frame in fixed relation to said tool and adapted to be moved concurrently with the 120

tool while the stylus is in contact with a guiding pattern and the cutting tool in contact with material to be operated upon, driving means on and movable with said carriage and connected with said tool for rotating the same, feeding mechanism comprising a feed screw rotatively mounted upon and movable with said carriage, a stationary threaded member in toothed engagement with said screw and adapted to effect the movement of the carriage when the feed screw is rotated, a handle supported on the tiltable frame, flexible connecting means connected with and forming a flexible connection between said handle and said feed screw and adapted to permit the tilting of the handle with the tiltable frame, feeding means supported on the carriage and operatively connected with the tiltable tool-supporting frame for moving the same at an angle relatively to the direction of movement of the carriage, and stationary supporting means adapted to support a pattern and material to be operated upon in fixed position in engagement with said stylus and tool respectively.

Signed at Chicago, in the county of Cook and State of Illinois, this 6th day of September, 1929.
